INVENTOR

UNITED STATES PATENT OFFICE.

THOMAS JAMES, OF BRADDOCK, PENNSYLVANIA.

MOTOR CONNECTION AND LOCK.

SPECIFICATION forming part of Letters Patent No. 501,904, dated July 18, 1893.

Application filed May 11, 1892. Serial No. 432,672. (No model.)

To all whom it may concern:

Be it known that I, THOMAS JAMES, of Brad-
dock, in the county of Allegheny and State of
Pennsylvania, have invented a new and use-
ful Improvement in Motor Connections and
Locks Therefor, of which the following is a full,
clear, and exact description, reference being
had to the accompanying drawings, forming
part of this specification, in which—

10 Figure 1 is a top plan view of a trolley for
a hoisting crane, provided with my improved
motor-connections; and Fig. 2 is a side eleva-
tion of the same.

15 My invention relates to the connections em-
ployed between power-driven shafts rotating
at a high speed and shafts driven therefrom
and arranged to rotate at a relatively low
speed, and more particularly to the motor-
connections employed upon hoisting cranes,
20 and is designed to greatly lessen the wear
upon the worm gearing at present employed
therein, as well as to secure a more positive
and certain action thereof.

25 To that end my invention consists of two
sets of gearing connecting the driving to the
driven shaft, one set being the ordinary worm
or screw-gearing now employed, and the other
a series of cog-wheels constituting a spur-gear-
ing, the said spur gearing being arranged to
30 work slightly in advance of the worm-gearing
in one direction of rotation, while the worm-
gear acts as a lock upon the spur gear and also
as a positive actuating connection when the
shaft is rotated in the opposite direction.

35 It also consists in the construction and ar-
rangement of the parts as hereinafter more
fully described and set forth in the claims.

40 In the drawings, in which like numerals in-
dicate corresponding parts, 2 represents the
frame of a trolley whose wheels 3, 3, are ar-
ranged to travel upon the jib of a crane in
the ordinary manner. Upon this trolley is
45 mounted a prime motor 4, in this case an elec-
tric motor, whose shaft 5 projects through the
bearing 6 and carries a pinion 7 and bevel-
wheel 8. A toothed wheel 9 engages the pin-
ion 7 and is carried upon a shaft 10 bearing
the screw or worm 11, which engages the
worm-wheel 12 upon the hollow drum shaft
50 13. A bevel-wheel 14 meshes with bevel-
wheel 8 and is carried upon a shaft 15 which
bears a pinion 16 secured thereto. With the

pinion 16 gears a large toothed-wheel 17 se-
cured to the shaft 18 passing through the hol-
low drum shaft and carried in bearings 19 55
upon the trolley-frame. Upon the shaft 18
is secured a pinion 20 intermeshing with
toothed wheel 21 upon an auxiliary shaft 22
carrying a pinion 22' gearing with a toothed
wheel 23 upon the hollow drum-shaft. A slow 60
motion is thus imparted to the drum, its rate
of speed corresponding to that derived through
the worm-gear, while the motion in this di-
rection is transmitted entirely through spur-
gearing. The intermeshing wheels 7 and 9 65
are so arranged that there is a slight amount
of lost motion therein. The effect of this is
that when it is desired to lift a weight, motion
is communicated to the drum shaft through
the bevel-gearing and the intermediate spur- 70
wheels and the worm gearing is not brought
into action. When, however, the weight is
lifted to the desired elevation and the motion
of the motor-shaft is arrested, the weight start-
ing to rotate the drum in the opposite direc- 75
tion, is held in its position by the worm-gear-
ing, which thereby forms a lock for the drum.
When the weight is to be lowered the motor
shaft being rotated in the opposite direction,
the wheels 7 and 9 directly engage each other 80
and the motion passes through the worm-
gearing. Under certain conditions as, for in-
stance, when a weight is lifted and deposited
upon a higher level, the worm-gearing acts as
a positive means for the reverse rotation of the 85
shaft as well as a lock therefor.

The advantages of my device are obvious.
As the strain and wear in lifting are borne
entirely by the system of spur gearing, no
wear of the worm-gear is incurred, while the 90
advantages of its use as a lock are retained.
Moreover, the worm-gearing now employed
absorbs about sixty or seventy per cent. of
the power exerted theron, only a small por-
tion being usefully employed in lifting the 95
load, whereas in my connection very little
power is lost, the lifting motion being trans-
mitted through the spur-gearing.

The connection is simple, positive in its ac-
tions, and not liable to get out of order, while
the life of the device is much longer than of
those now in use. I may employ an auto-
matic clutch to engage and rotate the worm
shaft after the engagement of the bevelgear-

ing, and many other arrangements of the spur and worm gearing may be employed without departing from my invention, which I regard as lying broadly in the connecting of two shafts by two sets of gearing, one a worm-gearing and the other a spur-gearing.

I claim as my invention—

1. A double connection between a driving and a driven shaft comprising a set of worm 10 gearing and a set of spur-gearing, the one set of gearing being arranged to act when the other is inactive and each adapted to rotate the driven shaft at the same speed; substantially as and for the purposes described.
- 15 2. A double connection between an actuating and a driven shaft, comprising a set of worm-gearing and a set of spur-gearing, the spur-gearing arranged to form the actuating connection in one direction of rotation, and 20 the worm-gearing as the actuating connection in the opposite direction of rotation and each adapted to rotate the driven shaft at the same speed; substantially as and for the purposes described.
- 25 3. A double connection between a driving and a driven shaft, comprising a set of worm-gearing having a slight amount of lost motion in its connection to the driving-shaft,

and a set of spur-gearing each adapted to rotate the driven shaft at the same speed; the 30 spur-gearing forming the actuating connection when the worm-gearing is inactive, and vice versa, substantially as described.

4. A shaft having a pinion and a bevel-wheel thereon, a toothed wheel engaging the 35 pinion and carried upon a shaft having a worm-gear connection with a winding shaft, a bevel wheel engaging the first named bevel-wheel, and connecting by a series of spur-gears with the winding shaft; substantially as described.

5. A shaft having a pinion and a bevel-wheel thereon, a toothed wheel engaging the 40 pinion with a slight amount of lost motion therein and carried upon a shaft having a worm gear connection with a winding shaft, a bevel-wheel engaging the first named bevel-wheel, and connecting by a series of spur gears with the winding shaft; substantially as described.

In testimony whereof I have hereunto set my hand this 4th day of May, A. D. 1892.

THOMAS JAMES.
